UNITED STATES PATENT OFFICE.

FRANK C. MACRI, OF BROOKLYN, NEW YORK.

LOCK.

Application filed May 6, 1924. Serial No. 711,303.

This invention relates to locks such as are used on the doors of houses or apartments, the invention having for an object to provide a novel form of key-controlled lock 5 characterized by difficulty in picking, while at the same time being of simple and inexpensive construction.

For further comprehension of the invention, and of the objects and advantages 10 thereof, reference will be had to the following description and accompanying drawing, and to the appended claims in which the various novel features of the invention are more particularly set forth.

15 Fig. 1 of the drawing is an inside face view of my improved lock with the cover plate removed.

Fig. 2 is a transverse vertical sectional view taken on the line 2—2 of Fig. 1.

20 Fig. 3 is a detail face view of the lock.

Fig. 4 is a horizontal sectional view taken on the line 4—4 of Fig. 1.

Fig. 5 is a detail perspective view of the key.

25 Fig. 6 is a fragmentary vertical sectional view showing more particularly the device for swinging the key-bit to operative position in the lock.

Fig. 7 is a similar view to Fig. 6 showing 30 the key partly withdrawn from the lock.

In constructing my improved lock I provide a rectangular plate 10 which is adapted to be secured, as by screws 11, to the inner face of the door to which the lock is applied, a portion of this door being indicated 35 at 12, and of the door frame at 13. Fixed to this plate 10 are a pair of straps 15 and 16 which form guide elements for the bolt 17 which latter is slidable along the plate. 40 The door frame 13 is provided with an ordinary keeper member 19 to receive the end of the bolt when the latter is moved to locking position.

45 Fixed to this bolt 17, between the two guide members 15, 16, is a plate 21 which is formed at opposite ends with the upwardly projecting fingers 22 which are adapted to be engaged by the key, as will be presently pointed out, to move the bolt from one position to the other. This plate 21 is adapted to bear on the guide strap 16 to limit the retracting movement of the bolt. A flat spring 23 is mounted on the plate 10 and bears on the bolt 17, and serves to provide a 50 friction device acting to hold the bolt in adjusted positions. Fixed to the bolt 17, is

a fin 24 which serves as a finger grip whereby the bolt may be retracted from within the house without the use of a key.

Formed in the plate 10 near the top thereof, is an aperture for insertion of the key which registers with an aperture in the door, a hollow cylindrical member or cap 26 being fixed on the back of the plate concentric to the said aperture, this cap having a vertical slot 27 entered therein from the bottom upward, the upper end of this slot being slightly above the centre of the cap, this slot permitting the key-bit to swing downward against the plate 10 into operative relation to the fingers 22 carried by the bolt. The parts above described are covered by a plate 27 suitably spaced from the plate 10, this plate being formed with horizontal and vertical slots 28 and 29 respectively which accommodate the fin 24 and the key-bit.

The key employed in connection with my improved lock is of novel construction and comprises the round shank 32 having a head 33 on one end and having the operating element or bit of the key in the form of a flat bar 34 hinged at one end to the other end of the shank, this bar being of a thickness to be accommodated in the slot 27 which latter is of less width than the diameter of the shank 32. Formed in the bit 34 are a number of ward notches 35 which are adapted to register with suitable elements on the back of the plate 10. As here shown one of these elements is formed by the flange on 55 the cap 26 and the others are formed by pins or studs 36 fixed to the plate 10.

In using the key, the latter is inserted through a circular aperture in the door 12, with the bit 34 alined with the shank 32. 95 When the end of the shank bears on the cap 26 the bit falls by gravity and lies along the plate 10 between the fingers 22 on the bolt and in close adjacency to the forward one of said fingers when the bolt is in retracted position, and by turning the key the bolt may be moved to locking position. To permit of swinging movement of the key-bit an arcuate recess 38 is formed in the flange on the cap 26. The key may be withdrawn by 100 simply pulling on the head 33, the bit first swinging to horizontal position.

In connection with my improved lock I provide a means for acting on the bit to swing the latter downward to operative position when the key is inserted in the lock. 110 As there shown a lever 42 is fulcrumed be-

tween its ends as at 43 to a projection 44 from the plate 10 and has its outer end inclined as shown at 45 to form a cam member adapted to be engaged by a pin 46 on the 5 key to swing the lever when the key is inserted. The inner end of the lever is formed with an offset 47 having an extended tip or point 48 which engages the key bit upon initial downward movement of the inner 10 end of the lever, and a shouldered element 49 which engages a shouldered element on the key bit to impart the final downward movement to the latter. The parts are as otherwise above described.

15 Having thus described my invention what I claim as new and desire to protect by Letters Patent of the United States is as follows:—

1. In a lock, a bolt formed with a pair 20 of elements spaced therealong for engagement by a key to move the bolt, a plate on which said bolt is slidably mounted, and a key comprising a shank and a pivoted bit, said bit being adapted to be swung at right 25 angles to the shank to lie along said plate

and engage the said elements, and a lever fulcrumed in the lock and adapted to be moved by said key to bear on said bit when the key is inserted in the lock to cause said bit to swing downward to position adjacent 30 said plate.

2. In a lock, a bolt formed with a pair of elements spaced therealong for engagement by a key to move the bolt, a plate on which 35 said bolt is slidably mounted, and a key comprising a shank and a pivoted bit, said bit being adapted to be swung at right angles to the shank to lie along said plate and engage the said elements, and means adapted to bear on said bit when the key is inserted in the lock to cause said bit to swing downward to position adjacent said plate, said means comprising a lever fulcrumed in the lock and having at one end a cam adapted to be engaged by the key and at its other end 40 an offset adapted to engage the said bit.

In testimony whereof I have affixed my signature.

FRANK C. MACRI.
